United States Patent Office.

NATHAN P. MAKER, OF PROVIDENCE, RHODE ISLAND.

Letters Patent No. 90,456, dated May 25, 1869.

IMPROVEMENT IN DROP-PRESS.

The Schedule referred to in these Letters Patent and making part of the same.

To all whom it may concern:

Be it known that I, NATHAN P. MAKER, of Providence, in the county of Providence, and State of Rhode Island, have invented a new and improved Adjustable Bed and Frame for Drops, Trip-Hammers, and Drills; and I do hereby declare that the following is a full, clear, and exact description thereof, which will enable others skilled in the art to make and use the same, reference being had to the accompanying drawings, forming part of this specification, in which—

Figure 1 represents a side elevation, partly in section, of my improved bed for drops.

Figure 2 is a plan or top view of the same.

Similar letters of reference indicate corresponding parts.

This invention relates to a new device for adjusting the bed of a power or hand drop press, trip-hammer, upright drill, or other similar machine, so that said bed may, at will, be placed into a horizontal or slanting position, as may be desired.

In trip-hammers and drops, it frequently occurs that the bed becomes displaced from the horizontal position by long wear, and it can, on the present machines, only be readjusted with the greatest difficulty. In boring-machines, it is often desirable to have the bed in an inclined position, so as to bore holes in the same direction through plates or other articles. By providing a bed or frame which can be readily adjusted, the above objects can be readily attained, and the difficulty overcome.

My invention consists in the bed, having its fixed base provided with a semispherical cavity, and the adjustable plate, provided with a semispherical projection, in combination with the oscillating frame and hammer, as will be hereinafter more fully described.

A, in the drawing, represents a fixed bed, made of cast-iron or other suitable material. From its sides project lugs, d d, so that the side-bars of the frame,

B, may be pivoted to the same, as shown, to allow the said frame to be inclined at will.

The frame can be pivoted in any other suitable manner, so as to be adjustable. It may, however, be also rigidly attached to the bed A, when either no inclination is desired, or when the bed can be inclined, as hereinafter set forth.

C represents the movable bed-plate. From its under side projects a semispherical block, D, which fits into a cavity provided in the bed A, the bed C being thereby allowed a slight adjustment on this globe-pivot.

When the bed C is adjusted so that its surface is level, it is clamped in the desired position, by means of screws, a a, or their equivalents.

Screws, b b, fitted through the bed C, serve to adjust it when they are turned.

When the cavity in the block A is shallower, or the block D is longer than a half globe, the plate C will receive more play, and can be swung into any desired inclined position. In that case, the swinging frame B is not needed.

It is evident that the bed C would be adjustable in the same degree, if the block D projected from the bed A into a cavity formed in the under side of C.

Having thus described my invention, I claim as new, and desire to secure by Letters Patent—

The bed for drops, trip-hammers, &c., consisting of the fixed base A, provided with the semispherical cavity, and the plate C, provided with the semispherical projection D, and adjusted by means of the set-screws a or b, in combination with the oscillating frame B, and the hammer, as herein described, for the purpose specified.

NATHAN P. MAKER.
